(57) **CLAIM**

The ornamental design for a heel protector, as shown and described.

DESCRIPTION

FIG. 1 is a perspective view of a heel protector.

FIG. 2 is a front view of the heel protector of FIG. 1.

FIG. 3 is a back perspective view of the heel protector of FIG. 1 with the point of view being closer to the bottom portion than the top portion.

FIG. 4 is a right-side view of the heel protector of FIG. 1.

FIG. 5 is a left-side view of the heel protector of FIG. 1.

FIG. 6 is a top view of the heel protector of FIG. 1; and, FIG. 7 is a bottom view of the heel protector of FIG. 1.

The broken lines in the drawings are for the purpose of

illustrating portions of a heel protector and form no part of the claim.
